UNITED STATES PATENT OFFICE

163,887

SPOON OR SIMILAR ARTICLE

Norman J. Mercer, Brooklyn, N. Y.

Application July 10, 1950, Serial No. 11,060

Term of patent 14 years

(Cl. D54—12)

To all whom it may concern:

Be it known that I, Norman J. Mercer, a citizen of the United States, and a resident of Brooklyn, county of Kings, and State of New York, have invented a new, original, and ornamental Design for a Spoon or Similar Article, of which the following is a specification, reference being had to the accompanying drawings, forming part hereof and in which:

Fig. 1 is a front elevational view of a spoon, showing my new design.

Fig. 2 is a side elevational view.

The essential features of my design for a spoon reside in the parts shown in the handle in full lines, it being understood that this design may be applied to knives, forks, and other articles of flatware without departing from the spirit of the invention.

I claim:

The ornamental design for a spoon or similar article, as shown and described.

NORMAN J. MERCER.
